UNITED STATES PATENT OFFICE

HUBERT HARRY HARSHMAN, OF TORONTO, ONTARIO, CANADA

DISPLAY CABINET OR CONTAINER FOR STATIONERY

Application filed May 5, 1928. Serial No. 275,487.

My invention relates to improvements in display cabinets or containers for stationery or other merchandise, and the object of the invention is to devise an adjustable retaining means, in a container having a downwardly and forwardly inclined top, for holding merchandise such as cards against a face of the cover so that when the cover is closed and the cards carried to an inverted position they will be definitely held in place and when the cover is raised to its open or substantially vertical position such retaining means may be adjusted to simultaneously release all the cards for the free withdrawal of any one card and yet hold the remaining cards in display position, and it consists essentially of the arrangement and construction of parts as hereinafter more particularly explained.

Fig. 1 is a perspective view of my cabinet or container shown in the open position.

Fig. 2 is a transverse sectional view showing the container in the closed position.

Fig. 3 is a fragmentary perspective detail shown partially in section of my retaining device.

Fig. 4 is a fragmentary perspective detail of the locking means by which both sides of the retaining means may be operated simultaneously from a central point between such sides.

Fig. 5 is an enlarged transverse sectional view through my container cover and retaining device and showing the locking means referred to in Figure 4.

In the drawing like characters of reference indicate corresponding parts in each figure.

1 indicates the body of the container which forms a receiving well provided with a forwardly and downwardly inclined top.

2 are a series of parallel inclined ledges forming at their lower ends receiving grooves or channels 3 in which the lower ends of the cards or other merchandise such as indicated at 4 are held, the top of the cards resting in an inclined position upon the ledge with their upper ends overhanging the upper edge of the ledge so that they can be easily gripped between the thumb and finger of the user for their withdrawal.

5 is my container cover hingedly connected at 6 at the upper end of the inclined top of the body 1. 7 are series of ledges or channels extending transversely of the container cover spaced a suitable distance apart and arranged parallel one to the other. The channels 7 are provided in proximity to each end with orifices 8 which are offset alternately in opposite directions longitudinally of the channels so as to be arranged in a generally zig zag vertical formation for a purpose which will hereinafter appear.

9 and 10 are a pair of parallel spring rods or stiff wires which are passed through the orifices 8 of all the channels 7. By zig zagging the position of the orifices the opposite ends of the alternative orifices frictionally engage the wire 9 or 10 to hold such wire from longitudinal movement and yet permit of such wire being forced by a slight manual pressure longitudinally. 9° is a stop pin or projection limiting the downward movement of each wire 9 or 10.

11 are series of transverse spring rods or wires which extend normally parallel to the channels 7 and are provided at their ends with enlargements 11° through which an adjusting screw 12 extends, the screw being held from longitudinal movement in such enlargement by collars 11° and 11°. The inner end of the stem of the screw is alone threaded and meshes with a correspondingly internally threaded orifice 13 formed in each wire 9 and 10. By turning the screws 12 the wires 11 may be adjusted inward or outward to more or less grip the cards 14 supported at their lower ends within the channels 7.

When the cover 5 is to be closed each of the wires 9 and 10, preferably at a point of intersection of the central transverse wire 11, is gripped so that the transverse wires 11 are moved into a position adjacent the top edges of the cards. When so adjusted the cover may be lowered to its closed position and the cards supported so that they will have no tendency to slip downward and forward out of their retained position. When the cover is open for display purposes the wires 9 and 10 are moved in the opposite direction so that the transverse wires 11 are adjusted to a position in

close proximity to the channels 7 and therefore, adjacent to the lower ends of the cards. This adjustment permits the major portion of the face of the card being clearly visible to 5 an intending purchaser and at the same time leaves the upper edges of the cards free so that they can be readily gripped between the thumb and finger of such purchaser and withdrawn for inspection and then returned to 10 place.

It will of course be understood that one or the other of the wires 9 or 10 may be moved longitudinally so as to permit cards either at one side or other of the cover being removed 15 if so desired.

Under certain circumstances it may be advisable to enable the operator to move the wires 9 and 10 simultaneously by the employment of one hand only. In order to permit 20 of this operation being performed the following mechanism is provided.

The wires 9 and 10 are provided at their outer sides with notches 9^x and 10^x arranged in horizontal alignment one with the other. 25 15 is a rigid bar provided at its ends with upwardly and downwardly extending arms 15^x and 15° provided with inturned ends 16 and 17 having orifices 16^x and 16° through which the wires 9 and 10 freely extend.

30 17 and 18 are spring pressed locking rods provided at their inner ends with finger grips 19 and 20, and at their outer ends with locking pieces 21 and 23. The rods 17 and 18 are spring pressed in their outward position so that the locking pieces 21 and 22 are out of engagement with the notches 9^x and 10^x. The rods 17 and 18 are slidably connected to the bar 15. When it is desired to move the rods 9 and 10 simultaneously by the employment of 40 one hand the finger grips 19 and 20 are gripped by the fingers of one hand and forced together against the pressure of the springs 17^x and 18^x thereby carrying the locking pieces into engagement with the notches 9 and 10. The hand still gripping the finger pieces 19 and 20 is moved up so as to simultaneously carry the rods 9 and 10 upward to their upper position or in opposite direction 45 when it is desired to return the rods 9 and 10 to their lower position.

From this description it will be seen that I have devised a very simple and easily operated means whereby cards or other like articles of merchandise may be held against the 55 face of a cover so that such cards will be held definitely in position when the cover is lowered to a downwardly inclined position and the cards carried towards an inverted position and yet may be quickly and easily adjusted 60 so that when the cover is raised such retaining means may be removed from the upper portion of the card face leaving it clearly visible to an intending purchaser, and so that this upper edge will be free permitting such upper 65 edge to spring slightly outward from the

cover so that such edge may be readily gripped between the thumb and finger of the purchaser and removed and returned as desired.

What I claim as my invention is:

1. In a display cabinet or container for stationery or other merchandise, the combination with a container cover, of a series of transverse supporting ledges carried on a face of the cover, a transverse retainer adjacent each ledge, and means carrying the retainers for simultaneously varying the distance between each ledge and transverse retainer. 70

2. In a display cabinet or container for stationery or other merchandise, the combination with a container cover, of a series of transverse supporting ledges carried on a face of the cover, a transverse retainer adjacent each ledge, and means carrying the retainers for simultaneously varying the distance between each ledge and transverse retainer so that the retainer alternatively assumes a position adjacent to or remote from the ledge and means on the retainer carrying means for adjusting the retainer to or from the face of the cover. 80

3. In a display cabinet or container for stationery or other merchandise, the combination with a container cover, of a series of transverse supporting ledges carried on the face of the cover, a transverse retainer adjacent each ledge, and means for carrying the retainers operable from a point centrally of the cover for simultaneously varying the distance between each ledge and transverse retainer so that the retainer may assume a position adjacent to or remote from the ledge. 90

4. In a display cabinet or container for stationery or other merchandise, the combination with a container cover, of a series of transverse supporting ledges carried on the face of the cover, parallel movable rods extending through the ends of each of the aforesaid ledges, transverse retainers carried by the rods and adapted to be moved to positions adjacent the ledges or to positions remote from the ledges. 100

5. In a display cabinet or container for stationery or other merchandise, the combination with a container cover, of a series of transverse supporting ledges carried on a face of the cover, parallel movable rods extending through the ends of each of the aforesaid ledges and having frictional engagement therewith and retainers carried by the rods. 110

6. In a display cabinet or container, the combination with a container cover, of ledges extending from the cover having orifices in each end thereof alternatively set in opposite directions, parallel movable rods extending through the alternative offset orifices to alternatively frictionally engage the alternate ends thereof, a transverse retainer carried by the rods and adapted to be moved to a posi- 120

tion adjacent a ledge or to a position remote from the ledge.

7. In a display cabinet or container for stationery or other merchandise, the combination with a container cover, of a series of transverse supporting ledges carried on a face of the cover, parallel movable rods extending through the ends of each of the aforesaid ledges, transverse retaining wires extending between the aforesaid parallel movable rods and adapted to be moved to positions adjacent the ledges or remote from the ledges, and a set screw connection through each transverse wire and movable rod.
- 15 8. In a display cabinet or container for stationery or other merchandise, the combination with a container cover, of a series of transverse supporting ledges carried on a face of the cover, longitudinal movable rods 20 slidably held in the ledges and having horizontally aligned notches therein, transverse retainers carried by the rods, a pair of finger grips located centrally between the rods, slide bars to the inner ends of which the finger 25 grips are connected provided at their opposite ends with inturned portions adapted to be carried into engagement with the notches when the finger grips are forced together, and spring means for carrying the finger 30 grips apart.
9. In a display device, a main supporting member, horizontal supporting means spaced suitable distances apart on the main supporting member, wires parallel to and spaced 35 from the horizontal supporting means, and means for movably supporting such wires so that they can be carried from positions remote from the horizontal supporting means to positions adjacent such horizontal supporting means.
